CLAIM

The ornamental design for a slide for a pistol, as shown and described.

DESCRIPTION

FIG. 1 is an upper, right, front perspective view of the slide for a pistol, showing my new design;

FIG. 2 is an upper, left, front perspective view thereof;

FIG. 3 is an upper, right, rear perspective view thereof;

FIG. 4 is an upper, left, rear perspective view thereof;

FIG. 5 is a right side view thereof;

FIG. 6 is a left side view thereof;

FIG. 7 is a top plan view thereof;

FIG. 8 is a bottom plan view thereof;

FIG. 9 is a front view thereof; and,

FIG. 10 is a rear view thereof.

The broken lines showing portions of the slide for a pistol as well as the broken lines showing environmental structure form no part of the claimed design.
